[57] CLAIM

The ornamental design for a protective terminal cover, as shown and described.

DESCRIPTION

FIG. 1 is a top, left-sided perspective view of a protective cover for a terminal;

FIG. 2 is a left-side elevation view;

FIG. 3 is a front view thereof;

FIG. 4 is a bottom plan view thereof;

FIG. 5 is a top plan view thereof;

FIG. 6 is a right-side elevational view thereof;

FIG. 7 is a back view; and,

FIG. 8 is a front perspective view of the cover wherein an attached pen and a terminal unit mounted therein are shown in broken lines for illustrative purposes only and form no part of the claimed design.

The pattern partially shown in FIGS. 3, 4, 5, and 7 is understood to represent conventional material.
